UNITED STATES PATENT OFFICE.

ALLAN G. LEFLER, OF BELLEVILLE, MICHIGAN.

CLAMP FOR STRETCHERS FOR STRETCHING FENCES.

No. 852,842.

Specification of Letters Patent.

Patented May 7, 1907.

Application filed February 27, 1907. Serial No. 359,559.

To all whom it may concern:

Be it known that I, ALLAN G. LEFLER, a citizen of the United States, residing at Belleville, R. F. D. No. 5, in the county of Wayne and State of Michigan, have invented 5 certain new and useful Improvements in Clamps for Stretchers for Stretching Fences, &c., of which the following is a specification.

This invention relates particularly to 10 clamps for stretchers adapted for use for stretching fence or other wires or stretching sheet metal or other material.

The object of the invention is to provide a 15 clamp which will quickly engage and firmly hold the material to be stretched, and which can be readily operated to release the same when desired, advantage being taken of the large power of a cam to effect the clamping action.

20 The invention is illustrated in the accompanying drawings, in which

Figure 1 is a front elevation of the clamp. Fig. 2 is a horizontal section thereof. Fig. 3 is a plan in detail of one of the clamping bolts.

25 Referring specifically to the drawings, 6 indicate a pair of angle bars between which the wires 7 are clamped. These angle bars are provided with suitable holes or devices whereby the chains or other tackle may be 30 attached. Also the respective bars have registering holes 8 and slots 9, which register when the bars are properly placed together. The holes 8 receive the clamping bolts 10, each of which is threaded at the end to receive 35 the adjusting nut 11 and is provided at the other end with a head 12 having on opposite sides thereof lugs 13. The other bar 6 has the slots 9 so that said bar may be placed or removed as necessary.

40 The cam lever is indicated at 14 having a head 15 which is forked or recessed, each fork or cheek having a slot 16 of proper size and shape to receive the lug 13 so that the forks may be hooked thereunder. Washers

17 are conveniently placed under the nut 11 45 and under the cam head 15.

In use, the wires 7 are first laid across the one bar 6 and then the other bar, the one having the slots 9, is put in place. The cam lever is then swung down or parallel to the 50 angle bars, thereby bearing against the angle irons and clamping the wires therebetween. If the bars are say four or five feet long three or four of these cam clamps can be used at various points along the bars. In addition to 55 gripping wire the device can very readily be used for gripping the edges of sheet metal or other material, which may be desired to be stretched. The nuts 11 allow the length of the bolts to be adjusted to accommodate 60 wires of different sizes.

I claim:

1. A fence clamp comprising two angle bars, a bolt connecting said bars, said bolt having a head and lugs projecting from the 65 sides of the head thereof, and a cam having forks engageable under the lugs, to tighten the bolts.

2. A clamp comprising two angle bars, one of the bars having a hole and the other having a slot registering therewith, a bolt extending through the hole and the slot, and having a head, and means to tighten said bolt comprising a cam engageable under the head thereof. 70

3. A clamp comprising a pair of angle bars, a bolt connecting the same, said bolt having a nut on one end and a head on the other, the head having laterally-extending lugs on opposite sides, and a cam having a recessed 80 head with opposite cheeks slotted to engage the said lugs. 75

In testimony whereof I affix my signature, in presence of two witnesses.

ALLAN G. LEFLER.
